GOLF CLUB HEAD

James M. Long, South Hadley, Mass., assignor to A. G. Spalding & Bros. Inc., Chicopee, Mass., a corporation of Delaware

Filed May 9, 1963, Ser. No. 74,824

Term of patent 14 years

(Cl. D34—5)

FIGURE 1 is a front view of a golf club head showing my new design;

FIG. 2 is a back view of the golf club head;

FIG. 3 is an end view of the golf club head; and

FIG. 4 is a top view of the golf club head.

The dominant features of my design reside in the portions shown in full lines, the blade for the head being characterized by having a concave upper edge extending along the blade, a back having a rounded end and a recess therein adjacent the concave edge, and a thin web connecting the blade portion to the hosel of the club all as shown.

I claim:

The ornamental design for a golf club head, as shown and described.
